(57) **CLAIM**

The ornamental design for a trim reveal extrusion, as shown and described.

DESCRIPTION

FIG. 1 is a perspective view of the trim reveal extrusion showing our new design.

FIG. 2 is another perspective view thereof.

FIG. 3 is an end elevational view thereof; and,

FIG. 4 is another end elevation view thereof, showing the trim reveal extrusion in a condition of use.

The broken lines shown in FIG. 4 illustrate environmental subject matter only and form no part of the claimed design. The trim reveal extrusion is shown with a symbolic break in its length. The appearance of any portion of the trim reveal extrusion between the break lines forms no part of the claimed design.
